UNITED STATES PATENT OFFICE.

EDMUND DE MOULIN AND ULYSSES S. DE MOULIN, OF GREENVILLE, ILLINOIS.

TRICK-CHAIR.

SPECIFICATION forming part of Letters Patent No. 642,092, dated January 30, 1900.

Application filed August 15, 1899. Serial No. 727,296. (No model.)

To all whom it may concern:

Be it known that we, EDMUND DE MOULIN and ULYSSES S. DE MOULIN, citizens of the United States, residing at Greenville, in the 5 county of Bond and State of Illinois, have invented a new and useful Chair, of which the following is a specification.

This invention relates to chairs in general, and more particularly to that class used in 10 secret organizations where the newly-admitted members are subjected to certain treatment known as "initiation;" and it has for its object to provide a construction in which the chair may be caused to suddenly fall backward but without injury to the occupant, the 15 particular object of the invention being to provide an arrangement of supporting-legs and latch mechanism through the medium of which the legs may be held in their operative 20 positions or be allowed to fold.

In the drawings forming a portion of this specification, and in which similar numerals of reference designate corresponding parts in the several views, Figure 1 is a perspective 25 view of the chair in its erect position. Fig. 2 is a vertical section of the lower portion of the chair and showing the latch mechanism. Fig. 3 is a view similar to Fig. 2, showing the latch released, the legs folded, and the chair 30 in a reclining position. Fig. 4 is a bottom plan view of the chair when the parts are locked in position. Fig. 5 is a view similar to Fig. 4, showing the elements of the structure after it has been sprung. Fig. 6 is a 35 bottom perspective showing the latch and releasing mechanism of the chair.

Referring now to the drawings, 10 represents the bottom of the chair, to the front of which are fixed parallel legs 11 and 12, having 15 attached to their lower ends arc-shaped rockers 13 and 14, which extend rearwardly and upwardly to the rear of the seat 10 and are thence continued upwardly of the back 15, so that the chair may have a rocking movement 20 thereon at times. Pivoted to the rockers 13 and 14 are additional legs 16 and 17, respectively, the upper ends of which have a common connection 18, to which is attached a spring 19, which when the said legs are in 25 their operative positions extends adjacent and rearwardly of the under side of the chair-bottom and through a clip 20, fixed to the chair-

bottom. The end of the spring 19 lies in the path of a lever 21, pivoted to parallel standards 22 and having attached thereto an operating-cord 23. This lever when operated by the cord 23 acts to press the extremity of the spring 19 in the direction of the bottom of the chair and to disengage its latch-barb 23 from the clip 20, said barb, when the legs 16 and 17 are in the position shown in Fig. 6, lying upon the rear face of the clip, it being understood that as the spring 19 enters the clip the tip thereof engages the clip and presses the spring in the direction of the bottom of the chair until the barb has passed through the clip, when the spring quality of the latch moves it outwardly and seats the barb behind the clip.

As shown in Fig. 1 of the drawings, when 70 the legs 16 and 17 are in their operative positions they partially support the weight of the chair, and, as shown in Fig. 3, said legs are arc-shaped and are adapted when folded to conform to the shape of the rockers 13 and 14, against which they lie. Thus if the chair be in its upright position and the cord 23 be drawn the latch will be disengaged from the clip 20, which forms a keeper therefor, thus 75 releasing the legs 16 and 17 and allowing them to fall against the rockers, at the same time the chair falling backwardly upon the rockers and lying finally in the position shown in Fig. 3 of the drawings.

In order to make the effect more startling 85 to the occupant of the chair, a cap-exploding apparatus is fixed to the bottom of the chair-seat and comprises a spring-keeper 30 in the path of the lever 21 and adapted to be depressed thereby when the latch-spring 19 is 90 released. This keeper 30 projects beyond the latch-spring, and the end of the latch-spring is beveled transversely, so that its rear edge is thicker than its front edge, as shown at 31. Pivoted to a standard 32 is a striker 33, having a hammer 34 at one end adapted to strike an anvil 35, upon which a cap may be placed, the opposite end of said striker being adapted for engagement with the beveled end of the keeper 30 to depress and pass over it and 95 finally to lie against the rear edge thereof and to be held thereby against the influence of a helical spring 36, the tendency of which is to move the hammer against the anvil. As

the striker engages the keeper the latter is depressed, and when the striker has passed beyond it it rises to hold the striker. Thus it will be seen that if a cap is placed upon 5 the anvil when the mechanism is operated to precipitate the chair the striking mechanism will be released and the cap will be exploded, and thus will the sensation be intensified.

In order to move the legs 16 and 17 in the 10 direction of their operative positions and from the rockers 13 and 14, a helical spring 50 is disposed upon the pivot-bar 51, through the medium of which the legs 16 and 17 are pivoted to the rockers and to which the legs 15 16 and 17 are fixed. One end of the spring is fixed to this pivot-bar, and the other end is fixed to the adjacent leg 16. A similar spring 53 is disposed adjacent to the leg 17. Thus when the chair is raised from its inclined position 20 the movable legs are in a position where they may be readily moved to engage the latch mechanism.

Having thus described the invention, what is claimed is—

- 25 1. A chair comprising a seat and a back rigidly connected, supports fixed to the seat, additional supports pivoted relatively to the seat, a connection between the pivoted supports, a latch adapted to engage said connection and hold the pivoted supports normally in operative position, a detonating mechanism, a common means for holding the latch and detonating mechanism and a common means for releasing the latch and detonating mechanism simultaneously.
- 30 2. A chair, comprising a seat and a back rigidly connected, supports fixed to the seat,

rockers having rigid connection with the seat, the back and the support, movable supports pivoted to the rockers and having a common 40 connection and adapted to hold the rockers normally in inoperative position, a latch adapted for engagement with said connection to hold the movable supports in operative position, and means for operating the latch to 45 release the movable supports.

3. A chair, comprising a seat and a back rigidly connected, supports fixed rigidly to the seat, rockers fixed to said supports and to the back and extending along the back, movable 50 supports connected to the rockers and adapted to hold them normally inoperative, a latch adapted to hold the movable supports in operative position, and means for operating the latch to release the movable supports. 55

4. A chair, comprising a seat and a back rigidly connected, rigid supports fixed to the seat, rockers fixed to the lower ends of the supports and to the back and extending along the back, movable supports pivoted to the 60 rockers and adapted to hold the rockers inoperative, a latch adapted to hold the movable supports in operative position, and means for operating the latch to release the movable supports. 65

In testimony that we claim the foregoing as our own we have hereto affixed our signatures in the presence of two witnesses.

EDMUND DE MOULIN.
ULYSSES S. DE MOULIN.
